UNITED STATES PATENT OFFICE

122,782

DESIGN FOR A BOWL OR ANALOGOUS ARTICLE

Gustave Muller, San Francisco, Calif.

Application January 8, 1940, Serial No. 89,346

Term of patent 3½ years

To all whom it may concern:

Be it known that I, Gustave Muller, a citizen of the United States, residing at San Francisco, in the county of San Francisco and State of California, have invented a new, original, and ornamental Design for a Bowl or Analogous Article, of which the following is a specification, reference being had to the accompanying drawing, forming a part thereof.

Fig. 1 is a side elevational view of a bowl or analogous article, showing my design;

Fig. 2 is an elevational view of the same taken at right angles to Fig. 1;

Fig. 3 is a top plan view of the same; and
Fig. 4 is a sectional view taken on the line 4—4 of Fig. 3.

I claim:

The ornamental design for a bowl or analogous article, substantially as shown.

GUSTAVE MULLER.
